UNITED STATES PATENT OFFICE.

EUGENE E. ANDERSON, OF KANSAS CITY, MISSOURI.

DESIGN FOR A GRIDDLE.

Application filed March 26, 1923. Serial No. 5,589. Term of patent 3½ years.

To all whom it may concern:

Be it known that I, EUGENE E. ANDERSON, a citizen of the United States, residing at Kansas City, county of Jackson, State of Missouri, have invented a new, original, and ornamental Design for Griddles, of which the following is a specification, reference being had to the accompanying drawing, forming part thereof.

Fig. 1 is a perspective view of my new, original and ornamental design.

Fig. 2 is a view in side elevation of the griddle shown in Fig. 1 at right angles to the position of the griddle as shown in Fig. 1.

I claim:

The ornamental design for a griddle as shown.

EUGENE E. ANDERSON.
